UNITED STATES PATENT OFFICE.

ABRAHAM GOLDBERG, OF BRONX, NEW YORK, ASSIGNOR TO TEXTO * METAL ART PRODUCTS CO., INC., OF NEW YORK, N. Y., A CORPORATION OF NEW YORK.

DESIGN FOR A LAMP STEM.

Application filed September 17, 1926. Serial No. 19,100. Term of patent 3½ years.

To all whom it may concern:

Be it known that I, ABRAHAM GOLDBERG, a citizen of the Republic of Russia, residing at 2519 St. Raymond Avenue, Bronx, county of Bronx, State of New York, United States of America, have invented a new, original, and ornamental Design for a Lamp Stem, of which the following is a specification, refer-

ence being had to the accompanying drawing, forming part thereof.

The figure is an elevation of a lamp stem showing my new design.

I claim:

The ornamental design for a lamp stem as shown.

ABRAHAM GOLDBERG.
